C. MALITCH.

RAIL CHAIR.

APPLICATION FILED JUNE 14, 1921.

1,390,919.

Patented Sept. 13, 1921.

UNITED STATES PATENT OFFICE.

CHARLES MALITCH, OF HAMILTON, OHIO.

RAIL-CHAIR.

1,390,919.

Specification of Letters Patent. Patented Sept. 13, 1921.

Application filed June 14, 1921. Serial No. 477,596.

To all whom it may concern:

Be it known that I, CHARLES MALITCH, a citizen of the United States, residing at Hamilton, in the county of Butler and State 5 of Ohio, have invented certain new and useful Improvements in Rail-Chairs, of which the following is a specification.

My invention, which generally has reference to that class of rail joints of boltless 10 construction, more particularly has reference to improvements in the particular form of rail chair disclosed in my Patent No. 958,964, dated May 24, 1910, and primarily my present invention has for its purpose to 15 render the construction of the form of the chair disclosed in my aforesaid patent more economical and more compact, and in which the means for holding the wooden wedges that clamp the adjacent faces of the rail 20 web and the chair, is simplified and yet effects the desired engagement with the wedges, and which tends to positively hold the wooden wedges from working loose or working endwise out of their rail and their 25 clamping adjustments.

My present invention includes in addition to the type of rail chair structures disclosed in my patent before referred to, a thin steel wedge that is held transversely 30 of the chair between the abutting ends of the rails and which has the cross sectional shape of the rail and whose rail web engaging portion, when the parts are assembled, extends laterally for entering into 35 the opposing wooden wedges, and with which is also combined a simple and effective means for holding the steel wedge from working upwardly and out from between the adjacent rail ends.

With other minor objects in view that 40 will appear in the following detailed description of my present construction of rail chair, specifically pointed out in the appended claims and illustrated in the accompanying drawings, in which:

Figure 1 is a perspective view of my improved construction of rail chair.

Fig. 2 is a horizontal section thereof taken particularly on the line 2—2 of Fig. 3.

Fig. 3 is a cross section taken on the line 3—3 on Fig. 2.

Fig. 4 is a perspective view of the steel wedge member hereinafter specifically referred to.

Fig. 5 is a detail horizontal section taken 55 on the line 5—5 of Fig. 3.

In the present development of my invention, the chair 2 is reduced to about 8 inches long and is adapted to sit down into a recess or seat 7^a in the end of the tie 7 and is held down on the said tie by a pair of spikes 5—5 at one side and a midway positioned single spike 5^a. The chair 2, in my present structure, has the opposite upwardly extending parallelly disposed webs 2^a—2^b 65 whose inner faces, as in my patented chair, lie in parallel planes, but are not parallel with the central longitudinal plane of the chair, as a whole, but lie at an angle thereto, to form wedge faces for coöperating with 70 the wooden tapered keys or wedge blocks 3—3 whose inner opposing faces are parallel with and engage the web of the rail, as is clearly shown in the drawing.

The base 2^a of the chair is chambered as 75 at 2^d, as stated, to conform to and receive the rail face 1^d, and the wooden bed plate 4 on which the rail ends rest, the several parts being substantially the same as the like ends shown in my patent referred to. 80

Instead of corrugating the inner faces of the wedge block 3, as in my patented construction, four V shaped grooves 6 are provided, one of said grooves 6 being formed in the inner face of each end of each of the 85 vertical webs 2^b of the chair 2 and into each of these notches or grooves 6, after the several parts that constitute my improved rail chair have been operatively assembled, is driven a steel tapered pin 60, 90 which is square in cross section, and which pins eat their way into the wooden wedges as they are driven in and they serve to firmly hold the wedges from creeping endwise from their rail wedging position. 95

For further holding the several parts to their firmly clamped position, a thin steel wedge plate 8 is employed, and it has substantially the cross sectional T shape of the head, and the web of the rail, the head portion of the said plate 8 being, however, of a slightly greater depth than the head portion of the rail to thereby provide ears 81 that project below or under the flange edges of the rail head (see Figs. 1 and 3) the web portion 82 of the plate 8 being also of a slightly greater width than the rail web and somewhat tapering to thereby cause the laterally

projected edges of the plate 8 to penetrate into the opposite wooden wedges 3 as the said steel wedge 8 is driven home and thereby serves to hold the wooden wedges more 5 securely in place.

The steel wedge member 8 is driven into the joint between the abutting rail ends after the wedges 3 have been applied and the pins 60 are driven into the grooves 6, and the 10 lower opposite ends of the head portion of the wedge constitute ears 81, each of which is apertured and projects below the opposite under face of the rail head, as shown in Fig. 3.

15 The ears 81 of the plate 8 receive cotter or split pins 9 which go through their respective apertures and fit under the flanges of the head of the rail and thereby prevent the wedge plate 8 from working loose and 20 being readily removed from between the rail ends.

By providing this steel wedge adapted to be driven between the adjacent ends of the two opposing rail members, a tight closure 25 between the rail ends is provided for, as also a supplemental means for gripping into and holding the wooden wedge members 3-3, which means in connection with the key pin devices 60 at the outer ends of the chair, and 30 which engage the chair and the wedge blocks 3-3, produce a simple and effective means for holding the wedges to their driven position and does away with the relatively expensive clamp screw devices necessary in my 35 patented construction and which, in practice, work loose and become detached from the rail chair by the jarring produced by the passing train. In my present construction, the means for holding the wedges 40 tightly up to their rail clamping position will not readily become loosened or thrown out of operative connection with the rail and the wedges or pin fasteners, as the steel wedge operates to positively maintain the 45 said wedge in its proper operative condition irrespective of any jars or shocks incident during the passing of trains thereover.

From the foregoing description taken in connection with the drawing, the complete 50 construction, the manner of its use and the advantages of my present invention will be readily apparent to those familiar with railway appliances of the kind to which my invention relates.

55 What I claim is:

1. A rail joint comprising in combination, a base adapted for being spiked onto a tie, the said base having a seat, a pair of opposing rail ends whose base portions are received in the chair seat, the chair having parallelly extending webs held in planes at an angle to their opposing rail web face, wooden wedge keys interposed between the chair and rail web faces, the opposite inner 60 ends of each chair web face having a V

shaped vertically extending groove and key pins square in cross section adapted for being driven into the said V shaped groove and to penetrate the wooden wedges and thereby lock them from displacement.

70 2. In a rail joint, a joint chair comprising a base having a rail base receiving seat and an upwardly extending web along each of the opposite longitudinal edges, the opposing faces of the chair webs and their corresponding rail web faces being angularly disposed whereby to provide tapering spaces that extend lengthwise between the chair webs and the rails, wooden wedge blocks fitting the said spaces, a steel filler plate having the cross sectional shape of the rail head and its web and adapted to be driven down between the adjacent ends of the rails, the web portion of the said plate being of greater width than the rail web whereby the 75 opposite edges of the web of the said plate penetrate the opposing wedge blocks as the said plates are driven home to thereby lock the blocks from movement.

80 3. In a rail joint, a joint chair comprising a base having a rail base receiving seat and an upwardly extending web along each of the opposite longitudinal edges, the opposing faces of the chair webs and their corresponding rail web faces being angularly disposed whereby to provide tapering spaces that extend lengthwise between the chair rail webs and the rails, wooden wedge blocks fitting the said spaces, a steel filler plate having the cross sectional shape of the rail head 85 and its web and adapted to be driven down between the adjacent ends of the rails, the web portion of the said plate being of greater width than the rail web whereby the opposite edges of the web of the said plate penetrate the opposing wedge blocks and lock them from movement, as the said plates are driven home, and means co-operating with the said plate and the rail head for holding the said plate to its indrawn position and 90 against working out from between the rail ends.

95 4. In a rail joint, a joint chair comprising a base having a rail base receiving seat and an upwardly extending web along each of the opposite longitudinal edges, the opposing faces of the chair webs and their corresponding rail web faces being angularly disposed whereby to provide tapering spaces that extend lengthwise between the chair 100 rail webs and the rails, wooden wedge blocks fitting the said spaces, a steel filler plate having the cross sectional shape of the rail head 105 and its web and adapted to be driven down between the adjacent ends of the rails, the web portion of the said plate being of greater width than the rail web whereby the opposite edges of the web of the said plate penetrate the opposing wedge blocks and lock them from movement as the said plates 110 are driven home, and means co-operating with the said plate and the rail head for holding the said plate to its indrawn position and against working out from between the rail ends.

115 5. In a rail joint, a joint chair comprising a base having a rail base receiving seat and an upwardly extending web along each of the opposite longitudinal edges, the opposing faces of the chair webs and their corresponding rail web faces being angularly disposed whereby to provide tapering spaces that extend lengthwise between the chair 120 rail webs and the rails, wooden wedge blocks fitting the said spaces, a steel filler plate having the cross sectional shape of the rail head 125 and its web and adapted to be driven down between the adjacent ends of the rails, the web portion of the said plate being of greater width than the rail web whereby the opposite edges of the web of the said plate penetrate the opposing wedge blocks and lock them from movement as the said plates 130

are driven home, the head portion of the said plate being of greater depth than the head portion of the rail to which it is applied whereby ear members on the plate 5 pendent from the under face of the rail flanges are provided, the said ear members being each apertured, and split pins adapted for passing through the apertured ears to lock the plate against being pulled upwardly 10 from the rail head.

5. In a rail joint, a joint chair comprising a base having a rail base receiving seat, and upwardly extending parallel webs spaced apart whose inner faces are parallelly disposed to one another and held in planes at 15

an angle to the central vertical longitudinal axis of the chair and the web of the rail, rails having their ends held in said chair, wooden wedge keys interposed between the chair webs and the rail web to secure the 20 rail immovable, a wooden bed plate in the rail base receiving seat under the rail ends, means for retaining said wedge keys in place, the said means comprising V shaped vertical grooves on the inner face of the chair webs 25 and tapering pins square in cross section adapted for being driven down into the said grooves to bite into the wooden wedge keys.

CHARLES MALITCH.
